THERMAL SWITCH

George C. Armstrong, Pittsburgh, Pa., assignor to
Westinghouse Electric Corporation, East Pitts-
burgh, Pa., a corporation of Pennsylvania

Original application April 3, 1945, Serial No.
586,287. Divided and this application August
15, 1946, Serial No. 690,631

7 Claims. (Cl. 200—122)

1

This invention relates to thermally operated electric contacts or relays, for instance, for overload protection, and is submitted as a division from my copending application Serial No. 586,287, filed April 3, 1945, for Relays, assigned to the assignee of the present application.

More particularly, my invention relates to electric contact devices which have a heatable container structure provided with quantities of mercury and volatile liquid respectively so that the mercury is displaced and changes its level when sufficient heat is applied to volatilize the liquid; and the change in level is used for causing the mercury to make or break an electric connection between contacts associated with the structure.

It is an object of my invention to provide devices of the just-mentioned type which are characterized by a much simpler design than heretofore available and which afford also the advantage of reduced space requirements.

According to the invention, a contact device is equipped with an electric or expandible container which encloses a quantity of mercury as well as a quantity of volatile liquid, and this container is associated with contact surfaces which are interconnected and disconnected by the mercury depending upon the change in volume of the container caused by the heat-responsive volatilization or condensation of the volatile liquid.

These and other features of the invention will be understood from the following description of those embodiments shown in Figs. 1, 2 and 3 respectively of the drawing.

In the embodiment shown in Figure 1, a body 1 of metal is connected by an elastic tube 2 with a contact 3 which is fastened to a terminal plate 4. Body 1 and plate 4 are provided with terminals 5 and 6, respectively, for connection to the circuit to be controlled by the relay unit. A quantity of mercury denoted by 7 is provided in the interior of the structure, and the remaining space within the central bore of body 1 contains an amount of volatile liquid denoted by 8. When the body 1 is heated, for instance, by a heating coil 10, the liquid 8, upon reaching its boiling point, evaporates and produces sufficient pressure to force the mercury 7 downwardly and out of contact with the body 1. The tubular portion 2 consists of a sufficiently elastic material, for instance, natural or synthetic rubber or a polyvinyl composition, such as polyvinyl alcohol or polyvinyl chloride. The connection of the elastic tube 2 with the body 1 and the contact 3 is sufficiently resistant and tight to permit an expan-

sion of the tube 2 without loosening it from the adjoining metal parts.

The modification shown in Fig. 2 has a metal body 11 which is provided with a terminal 12 and forms an axially projecting contact finger 13. A contact 14 with a terminal 15 is connected with the body 11 by a tube 16 of elastic material of the type mentioned above in conjunction with Fig. 1. The tube 16 encloses a quantity of mercury, denoted by 17, which normally establishes a conductive connection between the contact 14 and the contact finger 13. The annular space above the mercury 17 and around the finger 13 contains a quantity 18 of volatile liquid. Heating of the unit to a temperature above the boiling point of the liquid causes sudden evaporation of liquid 18 and hence increases the pressure above the mercury sufficiently to force it out of contact with the finger 13 under expansion of the tube 16.

The embodiment illustrated in Fig. 3 is of similar general type but contains an expansive bellows instead of the elastic tubes used in the relay units of Figs. 1 and 2. According to Fig. 3, a tubular metal part 19 is connected with a second tubular metal part 20 by an insulating seal or insert 21 consisting, for instance, of glass or other vitreous material. A bellows 22 is firmly secured to part 20. A quantity of mercury, denoted by 23, fills the interior of the structure to such an extent that it normally establishes an electric contact between the parts 19 and 20, and hence between the circuit leads 24 and 25 soldered or otherwise fastened thereto. A quantity of volatile liquid, denoted by 26, is disposed in the remaining space within the tubular part 19, and a heating coil 27 is provided for causing the liquid 26 to volatilize when the temperature exceeds the boiling point of the liquid. The pressure then developed within part 19 forces the mercury 23 downwardly under expansion of the bellows 22. As a result, the electric connection between parts 19 and 20 is interrupted.

Devices according to the invention may be used for overload protection of electric circuits and for this purpose are preferably mounted on an insulating base (not shown) of the general type described in the above-mentioned copending application.

Relays according to the invention and as described in the foregoing can be manufactured with extremely small overall dimensions as compared with known contact relays of comparable current capacity. This advantage, in conjunction with the small compass of the device, is particularly important for using the relays as a com-

ponent part of apparatus where space is at a premium. Since the use of mercury avoids the effects of friction and of variable spring pressure, the relay avoids an essential cause of failure occurring with relays of other types.

It will be understood by those skilled in the art that the invention is not limited to the specific embodiments shown in the figures, but can be modified as regards various details without departure from the essential features of the invention as set forth in the claims annexed hereto.

I claim as my invention:

1. An electric contact device, comprising a heatable and expandable container structure of variable volume having a quantity of mercury enclosed by said structure, a quantity of volatile liquid disposed in said structure so as to volatilize when sufficiently heated in order to then expand the volume of said structure, said container structure having two interior contact surfaces insulated from each other and engageable by said mercury quantity so as to be electrically interconnected and disconnected by said mercury quantity depending upon the change in mercury level caused by the change in volume of said structure.

2. An electric contact device, comprising a heatable and expandable container structure of variable volume consisting at least partly of metal and having two interior contact surfaces insulated from each other, and a quantity of mercury enclosed by said structure, a quantity of volatile liquid disposed in said structure so as to volatilize when sufficiently heated in order to then expand the volume of said structure, an electric heating coil disposed on said metal part of said structure for heating said liquid, said surfaces being electrically interconnected by said mercury quantity in a given volume condition of said structure.

3. An electric contact device, comprising a variable-volume container structure having two rigid metallic end portions and an intermediate portion of insulating elastic material, a quantity of mercury disposed in said structure so as to normally contact said two end portions, and a quantity of volatile liquid disposed in said structure so as to volatilize when sufficiently heated in order to then expand said intermediate portion whereby said mercury quantity changes its level and electrically disconnects said end portions.

4. An electric contact device, comprising a variable-volume container structure having an expandable bellows and being provided with two interior contact surfaces insulated from each other, a quantity of mercury enclosed by said structure, a quantity of volatile liquid disposed in said structure so as to volatilize when sufficiently heated in order to then increase the volume of

said structure by expanding said bellows, said surfaces being arranged relative to said mercury quantity so as to be electrically interconnected and disconnected by the mercury depending upon the change in mercury level caused by the change in volume of said structure.

5. An electric contact device, comprising a variable-volume container structure having a tubular and substantially rigid portion and an expandable and metallic bellows portion and an insulating annular portion disposed between said tubular portion and said bellows portion, a quantity of mercury disposed in said structure for establishing electric contact between said tubular portion and said bellows portion, and a quantity of volatile liquid disposed in said structure so as to volatilize when sufficiently heated in order to then expand said bellows portion whereby said mercury quantity changes its level and electrically disconnects said end portions.

6. An electric contact device, comprising a variable-volume container structure having a tubular and substantially rigid portion and an expandable and metallic bellows portion and an insulating annular portion of vitreous material forming a seal between said tubular portion and said bellows portion, a quantity of mercury disposed in said structure for establishing electric contact between said tubular portion and said bellows portion, and a quantity of volatile liquid disposed in said structure so as to volatilize when sufficiently heated in order to then expand said bellows portion whereby said mercury quantity changes its level and electrically disconnects said end portions.

7. An electric contact device, comprising a variable-volume container structure having a tubular and substantially rigid portion and an expandable and metallic bellows portion and an insulating annular portion disposed between said tubular portion and said bellows portion, a quantity of mercury disposed in said structure for establishing electric contact between said tubular portion and said bellows portion, and a quantity of volatile liquid disposed in said structure so as to volatilize when sufficiently heated in order to then expand said bellows portion whereby said mercury quantity changes its level and electrically disconnects said end portions, and an electric heating coil disposed on said tubular portion for heating said liquid.
